UNITED STATES PATENT OFFICE.

DAVID J. DOLAN, OF DETROIT, MICHIGAN, ASSIGNOR TO BURRELL TRIPP, TRUSTEE, OF ALLEGAN, MICHIGAN.

SWITCH-LOCK.

1,281,583.

Specification of Letters Patent.

Patented Oct. 15, 1918.

Application filed March 7, 1918. Serial No. 220,892.

To all whom it may concern:

Be it known that I, DAVID J. DOLAN, a citizen of the United States of America, residing at Detroit, in the county of Wayne and State of Michigan, have invented certain new and useful Improvements in Switch-Locks, of which the following is a specification, reference being had therein to the accompanying drawings.

10 This invention relates to switch locks and refers more particularly to a switch lock mechanism whereby when the switch is in neutral the circuit is established which will intercept any current that will go through 15 the system and carry it back to the ground.

The application is in part a continuation of my earlier filed application Serial Number 160,148, filed April 6, 1917.

20 In switch locks of the type applied to automobiles difficulty has been encountered in preventing theft by the use of the switch lock owing to the fact that the car could be rendered operative by connecting a lead from the magneto or battery to the coil-box 25 by running a wire from such lead to one of the high tension leads of the coil-box, the current then passing downward through the coil to the base-plate of the coil-box and through the primary windings of the other 30 coils to the timer.

35 In the present invention I have overcome this difficulty by the provision of a member which will close the auxiliary circuit to the ground whenever the switch is in neutral, thereby rendering inoperative any attempt to short circuit around the coils in the manner above described.

40 The invention also resides in such features of constructions and arrangements and combinations of parts as will more fully herein-after appear.

In the drawings:

45 Figure 1 is a front elevational view showing a switch lock embodying my invention, the cover plate being removed;

Fig. 2 is vertical sectional view through the switch lock;

Fig. 3 is a view similar to Fig. 1 showing a modified construction;

50 Fig. 4 is a diagrammatic view of the circuit in which the switch is employed.

Describing first in detail the general system to which the lock is applied, A designates a coil-box of an automobile and B, B',

B² and B³ the individual coils which, at 55 their lower ends, rest upon spring contacts C, C', C² and C³ connected to a base-plate D from which a lead wire D' extends to the movable member E of the switch. Each of the coils is provided with a high tension 60 lead or connection F, F', F², F³ leading to the spark-plugs G, G'. The current from the magneto J through the low tension coils is controlled by a timer H which successively closes the circuit through the low tension coil connections, I, I', I² and I³.

In certain types of automobiles there is also employed a battery such as L and the same switch when turned in the opposite direction connects the coils to the battery. 70

In the detailed construction of the switch as shown in Figs. 1, 2 and 3 and describing first the construction shown in Fig. 1, M designates the lead from the magneto and M' the lead from the battery, each of which 75 is connected to its respective spring contacts N and N'. O designates the stationary spring contact which is always engaged by the segmental contact maker O', the movement of which is governed by lock mechanism P, the detailed construction of which *per se* forms no part of the present invention. The arrangement of parts is such that when the proper key is inserted in the lock 80 P and turned toward the right it will throw 85 the end of the contact maker O' into engagement with the spring contact N and close the lead to the magneto, thus allowing the car to run in its usual manner. If, however, the key is turned to the left the opposite end of the contact maker O' will be engaged with the spring contact N', thus connecting the battery to the coils. 90

However, such locks are not entirely theft-proof owing to the fact that the unauthorized use of the car could be made possible by connecting a wire, such as indicated by the zig-zag line Q, from the magneto lead to one of the high tension coil connections such as F, allowing the current to flow 100 downward to the base-plate and then through the coils in the usual manner. It is the prevention of this unauthorized use that the present invention is particularly designed for and in the construction shown 105 in Fig. 1 is accomplished in the following manner:

In this construction I employ a plate

- member R which, when the switch is in neutral as shown in Fig. 1, will bring the ends R' and R² into engagement with the spring contacts N and N'. Therefore, if anyone attempts to run the car when the switch is locked by using a wire Q from the magneto the ignition circuit will not operate since the current will simply flow down to the base-plate and then in place of going upward through the coils to the spark-plug, it will be passed through the lead D', plate R, casing S and strap S' back to the ground on the car (indicated at K in Fig. 4). If an attempt is made to run the car by taking the battery and connecting it to the battery side of the coils the current from the battery will simply pass through the contact N', plate R, casing S and strap S' back to the ground.
- In the construction shown in Fig. 3 the same general result is obtained by an intercepting switch plate T slipped into the key slots T' so that it will turn with the contact maker O'. Thus when this type of switch is turned to neutral position, shown in Fig. 3, the end T² of the intercepting switch plate T will engage with the contact O which in turn is connected to the bottom plate D. Therefore any attempt to use the car when the switch is in neutral position by employing short circuiting or other wires Q and Q' will be prevented since the current flowing through such wires to the coils will be led back through the base-plate, the lead line D' and the intercepting plate T, the casing S and strap S' to the ground.
- The invention, however, is not limited to the two embodiments of my invention shown and described as various other forms of intercepting switch plates or like mechanism can be employed without departing from the scope of my invention.

What I claim as my invention is:—

1. The combination with a lead from a source of electric current, of coils, a switch for controlling the connection between the coils and the source of current, and a device for rendering the coils inoperative whenever the switch is thrown into neutral position. 45
2. The combination with a lead from a source of current, of an ignition circuit, a switch for controlling the connection between the ignition circuit and the source of current, said switch having an operative and a neutral position, and a member automatically adjusted by movement of the switch to neutral position for grounding the current in case the connection is made from the source of current to the ignition system without getting through the switch. 50
3. The combination with the ignition circuit of an automobile or the like including the coils, ignition devices electrically connected thereto, a magneto or the like, a switch for connecting the magneto to the coils, said switch having a neutral position wherein the circuit from the magneto to the coils is broken, and an intercepting device adjusted by the switch to neutral position for grounding the magneto lead whenever an attempt is 55 made to operate the ignition circuit when the switch is in neutral position. 60
4. The combination with an ignition circuit of an automobile or the like, of a key-operated switch for controlling said circuit, 75 said switch having a movable contact member movable to a neutral position, and an intercepting plate automatically adjusted into operative position upon movement of the movable contact of the switch to neutral 80 position.

In testimony whereof I affix my signature.

DAVID J. DOLAN.
